METALLIC SHEET ROOFING

Oliver G. Burriss, Anderson, S. C., assignor of forty one-hundredths to E. P. Vandiver and forty one-hundredths to John C. Taylor, both of Anderson, S. C.

Application February 14, 1935, Serial No. 6,576

4 Claims. (Cl. 108—22)

My invention relates to improvements in metallic roofing.

An important object of the invention is to provide a metallic sheet roofing element or shingle so constructed that it may be securely attached to the roof without the employment of separate attaching elements or strips, and which will interlock with a companion element or shingle for forming a water-tight joint.

10. A further object of the invention is to construct the roofing element or shingle so that it may be quickly and conveniently moved into interlocking relation with the companion elements or shingles.
15. A further object of the invention is to provide means to collect and drain any water which may possibly pass the interlocking joints and ribs of the assembled elements or shingles, thus preventing the same from passing to the roof.
20. A further object of the invention is to provide means whereby the attaching elements of adjacent shingles will overlap, and parts of the adjacent ribs will also have the maximum overlapping arrangement.

25. Other objects and advantages of the invention will be apparent during the course of the following description.

In the accompanying drawing forming a part of this application and in which like numerals 30 are employed to designate like parts throughout the same,

Figure 1 is a plan view of a plurality of assembled roofing elements or shingles.

Figure 2 is a transverse section taken on line 35 2—2 of Figure 1.

Figure 3 is a perspective view of the roofing element or shingle,

Figure 4 is an enlarged perspective view of the rear end of the shingle,

40. Figure 5 is a similar view of the forward end of the shingle, and,

Figure 6 is an enlarged detailed section taken on line 6—6 of Figure 1.

In the drawing wherein for the purpose of illustration is shown a preferred embodiment of my invention, the numeral 10 designates a metallic roofing element or shingle, formed of sheet metal or the like, which may be suitably resilient. This metal shingle is provided at one longitudinal edge with a hollow rib or bead 11, which is preferably circularly curved in cross-section, and open at its ends, and also open at its inner side, affording a longitudinal passage 12. This rib 11 is substantially semi-cylindrical, and extends above the shingle 10 and has its open side arranged

innermost with respect to the shingle, so that the passage 12 is adjacent to the shingle. The hollow rib or bead 11 is formed by bending the material of the sheet 10 upon itself in an inward direction, forming an inner layer or sheet 13, and then bending the sheet upon the edge 14, back upon itself in an outward direction, affording an outer sheet or layer 15, preferably snugly engaging the inner layer or sheet 13. The outer layer or sheet 15 is continued to a point substantially opposite 10 the passage 12, as shown at 15', and is then bent horizontally to afford an attaching extension or flange 16, flush with the sheet 10 or body portion of the shingle. The attaching extension or flange 16 is provided with an upwardly bulging 15 longitudinal rib 17, coacting with the hollow rib or bead 11, to afford a drain trough, for any water which may possibly pass over the hollow rib or bead 11. The attaching extension or flange 16 is preferably equipped with openings 18, for 20 receiving nails or the like which are employed to securely connect the extension or flange 16 with the roof.

The rib or bead 11, near its forward end, has its upper layer 15 cut away along a transverse 25 diagonal line 19, which diagonal line or edge 19 extends from the edge 14 to a point 20 at the forward end of the attaching extension or flange 16. This leaves a rib extension 21, formed by the forward end of the inner layer 13, and this rib 30 extension 21 preferably tapers forwardly, so that it may be readily passed into the rear end of the bead 11 of a companion shingle. The forward end of the attaching extension or flange 16, terminating at the point 20, is foreshortened with respect 35 to the forward end of the shingle. However, the forward end of the attaching extension or flange 16 projects forwardly for a substantial distance beyond the point 14', as shown, since the diagonal line or edge 19 is inclined in a manner to extend 40 forwardly toward the attaching extension or flange 16.

At its rear end, the rib or bead 11 is cut for producing a diagonal edge 22, which extends through both inner and outer layers 13 and 15, 45 and this diagonal edge 22 extends from the rear straight transverse edge 23 of the attaching extension to a point 16', which is spaced forwardly of the rear edge 23. The rear edge 23 forms a straight angle with the rear edge 23' of the shingle 10. The edges 19 and 22 are both diagonal or inclined, but they are inclined in opposite directions, the forward edge 19 being inclined forwardly toward the attaching flange or extension 16, while the rear edge 22 is inclined rearwardly 50 55

toward the extension or flange 16. The edges 19 and 22 may be said to be inclined and converge inwardly toward the shingle.

The opposite or longitudinal edge of the shingle 10 is bent to provide a hollow rib or bead 24, projecting above the same, and having its lower edge 25 substantially flush with the lower surface of the shingle and spaced therefrom, affording a passage 26. The forward end of the hollow bead 24 is cut away from a point 27, to a point 28, affording a diagonal edge 29, which aids in the application of the rib 24 to the corresponding rib of a companion shingle.

In assembling the shingles, the lowermost shingle 10 in one upstanding row is first placed upon the roof adjacent to the lower edge of the roof so that the shingle may suitably project below this lower edge and be properly attached to the lower edge. The attaching extension or flange 16 of this forward shingle is now attached or nailed to the roof. The next shingle 10 in the same row is now placed above or rearwardly of the first shingle, with its tapered extension 21 in the forward position. The next companion shingle may be slightly transversely inclined, and the rear end of the bead 24 of the forward shingle will be guided into the forward end of the bead 24 of the companion rear shingle, by virtue of the diagonal edge 29. After the insertion has been started, the next rear shingle is swung downwardly to a flat position upon the rear end of the forward shingle, the forward tapered extension 21 of the rear shingle is inserted in the rear end of the rib 11 of the forward shingle, and the rear shingle is now moved forwardly. The forward end of the attaching extension 16 of the rear shingle is disposed above the rear end of the attaching extension 16 of the forward shingle and these extensions accordingly overlap while the rear diagonal edge 22 of the forward shingle passes beneath the forward diagonal edge 19 of the rear shingle, and the rear shingle moved forwardly until the diagonal edge 19 engages the point of bending 14', or moves so close to it that binding action occurs. It is thus seen that not only do the adjacent ends of the attaching extensions 16 overlap, but the adjacent edges 22 and 19 overlap throughout substantially their entire length and this construction affords a very tight joint. The attaching extension or flange 16 of the rear shingle is now nailed or secured to the roof and each succeeding rear shingle is placed into position in a similar manner. After one upstanding row of shingles is thus layed, the next upstanding row is layed by applying the bead or rib 24 of the forward shingle to the assembled beads 11 and moving the forward shingle forwardly until it reaches a position to break joint with the said shingle of the first row. This forward shingle of the second row may be a whole shingle which is subsequently cut off, or it may be a half shingle. Each succeeding shingle in the second row is brought into position in a corresponding manner and overlapped and interlocked with the next forward shingle as described in connection with the shingles in the first row.

It is to be understood that the form of my invention herewith shown and described is to be taken as a preferred example of the same and that various changes in the size, shape and arrangement of parts may be resorted to without departing from the spirit of my invention or the scope of the subjoined claims.

Having thus described my invention, I claim:

1. A metallic shingle having its material at

one longitudinal edge bent over the same for affording a longitudinal hollow bead, said bead having inner and outer layers and an inner longitudinal edge spaced from the upper surface of the shingle for affording a longitudinal passage, an attaching extension permanently secured to the outer layer and having its forward end foreshortened and spaced from the forward end of the shingle, said bead having its outer layer near its forward end cut away for affording a diagonal edge, said diagonal edge extending from said inner longitudinal edge at a point spaced rearwardly from the forward end of the attaching extension to said forward end of the attaching extension, the inner layer projecting forwardly beyond the diagonal edge of the upper layer for providing a bead extension, said bead at its rear end being cut through both the inner and outer layers thereof for affording a rear diagonal edge which extends from the rear end of the shingle to said longitudinal edge at a point spaced forwardly from the rear end of the shingle, said shingle being provided at its opposite longitudinal edge with a hollow rib having a longitudinal passage.

2. A metallic shingle having its material at one longitudinal edge bent over the same for affording a longitudinal hollow bead, said bead having inner and outer layers and an inner longitudinal edge spaced from the upper surface of the shingle for affording a longitudinal passage, an attaching extension permanently secured to the outer layer and having its forward end foreshortened and spaced from the forward end of the shingle, said bead having its outer layer near its forward end cut away for affording a diagonal edge, the inner layer projecting forwardly beyond the diagonal edge for providing a bead extension, said bead being provided at its rear end with a diagonal edge, said diagonal edges being inclined in opposite directions, said shingle being provided at its opposite longitudinal edge with a hollow rib having a longitudinal passage.

3. A metallic shingle having its material at one longitudinal edge bent over the same for affording a longitudinal hollow bead, said bead having inner and outer layers and an inner longitudinal edge spaced from the upper surface of the shingle for affording a longitudinal passage, an attaching extension permanently secured to the bead and having its forward end foreshortened and spaced from the forward end of the shingle, said bead having its outer layer near its forward end cut away for affording a diagonal edge which is inclined rearwardly toward the shingle, the inner layer projecting forwardly beyond the diagonal edge for providing a bead extension, said bead being provided at its rear end with a diagonal edge which is inclined rearwardly toward the extension.

4. A metallic shingle having its material at one longitudinal edge bent over the same for affording a longitudinal hollow bead, said bead having inner and outer layers and an inner longitudinal edge spaced from the upper surface of the shingle for affording a longitudinal passage, an attaching extension permanently secured to the outer layer and having its forward end foreshortened and spaced from the forward end of the shingle, said bead having its outer layer near its forward end cut away for affording a diagonal edge, said diagonal edge extending from said inner longitudinal edge at a point spaced rearwardly from the forward end of the attaching

extension to said forward end of the attaching extension, the inner layer projecting forwardly beyond the diagonal edge of the upper layer for providing a bead extension, said bead at its rear end having a transverse edge, the arrangement being such that the rear transverse edge of the bead of the next forward shingle is passed between the inner and outer layers of the bead of the companion rear shingle and is guided by the

diagonal edge at the forward end of the upper layer of the rear companion shingle, the attaching extension of the rear companion shingle being arranged above and overlapping the rear end of the attaching extension of the forward shingle, each shingle being provided at its opposite longitudinal edge with a hollow rib having a longitudinal passage.
